UNITED STATES PATENT OFFICE

CHARLES HENRY APPLEMAN, OF BROOKLYN, NEW YORK, ASSIGNOR TO ALEXANDER AMITIN, OF BROOKLYN, NEW YORK

DESIGN FOR A STAND BASE

Application filed March 22, 1929. Serial No. 30,591. Term of patent 3½ years.

To all whom it may concern:

Be it known that I, CHARLES HENRY APPLEMAN, a citizen of the United States, and a resident of the borough of Brooklyn, county of Kings, city and State of New York, have invented a new, original, and ornamental Design for a Stand Base, of which the following is a specification, reference being had to the accompanying drawings, forming a part hereof.

Referring to the annexed sheet of drawings, Fig. 1 is a plan view of my design for a stand base; and

Fig. 2 is a side elevation thereof.

Fig. 3 is a central section through the base taken substantially on the line 3—3 of Fig. 1.

I claim:

The ornamental design for a stand base, substantially as shown.

CHARLES HENRY APPLEMAN.
